UNITED STATES PATENT OFFICE.

MARTIN E. LINDEMUTH, OF ELIZABETHTOWN, PENNSYLVANIA.

CAPONIZING-RACK.

1,381,717.

Specification of Letters Patent. Patented June 14, 1921.

Application filed September 14, 1920. Serial No. 410,109.

To all whom it may concern:

Be it known that MARTIN E. LINDEMUTH, a citizen of the United States of America, residing at Elizabethtown, in the county of 5 Lancaster and State of Pennsylvania, has invented new and useful Improvements in Caponizing-Racks, of which the following is a specification.

The object of the invention is to provide

10 a simple and inexpensive and at the same time effective means for properly positioning and holding a fowl during the caponizing process, without subjecting the fowl to unnecessary inconvenience or injury and 15 under such conditions as to avoid interference with the progress of the operation, and at the same time to provide a device for the purpose indicated which may be folded into compact form for storage and 20 transportation; and with these objects in view the invention consists in the construction and combination of parts of which a preferred embodiment is shown in the drawing wherein:

25 Figure 1 is a side view of the apparatus. Fig. 2 is a plan view of the same.

Figs. 3 and 4 are opposite end views respectively thereof.

Base 10 of the rack consists of a bar

30 mounted upon a turn table 11 which is swiveled, as by means of a bolt 12 to a suitable stand or support indicated at 13 and which may consist of any suitable upright such as a tripod or the equivalent 35 thereof, the base bar being capable of lateral tilted movement in either direction by reason of the double hinge connection consisting of the hinge pins 14 and 15 provided with coiled springs 16 to permit of retaining the 40 base bar either in an intermediate or normal or neutral position or turning the same laterally to either side, for the purpose of positioning the fowl with reference to the convenience of the operation. In the con-

45 struction illustrated the double hinge joint includes a hinge plate 17 connected by the hinge pins 14 and 15, which are mounted in the hinge eyes 18, respectively with the base bar 10 and turn table 11 as will 50 be seen clearly by reference to Fig. 4. Hingedly mounted as at 19 upon the base bar is a head rest 20 adapted to occupy an inclined position as indicated in Fig. 1 and to be secured in such position by means of 55 a retaining hook 21, said head rest being provided with tapered slots 22 forming a

double fork for engagement with the wings of the fowl, and mounted for adjustment longitudinally of the base bar is a foot rest 23, occupying a substantially upright or vertical position and having lugs 24 for engagement with guide grooves 25 in the side surfaces of the base bar, to the end that said foot rest may be adjusted along to the base bar to accommodate the length of the fowl, 60 and said foot rest being provided with tapered slots 26 for engagement with the legs of the fowl, which may further be secured to provide against movement or displacement during the operation, by a retaining cord or strap 27 attached as at 28 to the rest and engageable at its free end by a clip 29. Obviously the retaining strap or cord may be passed over the legs of the fowl after the latter have been positioned 75 in the slots 26, to hold the same in proper positions.

The head rest being hinged to the base bar may be folded inwardly after disengaging the hook 21, and the foot rest may be disengaged from the base bar and arranged in a flat relation to or in parallelism with the head rest and base bar, for convenience in storing the apparatus when not in use.

Having described the invention, I claim:

1. A caponizing rack having a base bar, an inclined head rest, and an upright foot rest mounted upon said base bar, both of said rests being provided with terminally open slots for the reception respectively of 90 the wings and feet of a fowl.

2. A caponizing rack having a base bar, a head rest hingedly mounted upon the bar, and a foot rest slidably mounted upon the bar for adjustment toward and from the 95 head rest, said head rest and foot rest being provided with terminally open pairs of tapered slots for the reception respectively of the wings and feet of a fowl.

3. A caponizing rack having a base bar 100 on opposite sides with longitudinal grooves, a head rest hingedly mounted upon the base bar, a retaining hook for securing the head rest in an inclined position with relation to the plane of the base bar, and a foot rest 105 provided with lugs for engagement with said grooves to permit of adjustment of the foot rest longitudinally of the base bar, said head rest and foot rest being provided with terminally open pairs of tapered slots 110 for the reception respectively of the wings and feet of a fowl.

4. A caponizing rack having a base bar provided with spaced head and foot rests provided respectively with pairs of terminally open tapered slots for the reception 5 respectively of the wings and feet of a fowl, and a flexible retainer secured to the foot rest for securing the feet of a fowl in the

slots thereof, the same consisting of a cord attached to the foot rest for spanning relation with the slots therein and a clip for 10 engaging the free end of said cord.

In testimony whereof he affixes his signature.

MARTIN E. LINDEMUTH.
